UNITED STATES PATENT OFFICE.

RUFUS K. MULFORD, OF BOSTON, MASSACHUSETTS.

KEY-GUIDE.

1,088,237.

Specification of Letters Patent. Patented Feb. 24, 1914.

Application filed March 1, 1913. Serial No. 751,590.

To all whom it may concern:

Be it known that I, RUFUS K. MULFORD, a citizen of the United States, residing at Boston, in the county of Suffolk and State 5 of Massachusetts, have invented certain new and useful Improvements in Key-Guides, of which the following is a specification.

This invention relates to key guides for the key-hole of doors, gates, windows, and 10 like structures which are provided with locks.

The principal object of this invention resides in the provision of a device which will 15 guide a key to the key-hole if it is applied to the face plate of the lock within a reasonable radius of the hole, thereby obviating the difficulty attendant upon inserting a key into a lock in the dark.

A further object of this invention is to 20 construct the key-guide with such regard to proportion, number and arrangement of parts that it may be cheaply manufactured and may be readily and conveniently applied to any lock of standard type.

The above and additional objects are 25 accomplished by such means as are illustrated in the accompanying drawings, described in the following specification and then more particularly pointed out in the claim which 30 is appended hereto and forms a part of this specification.

With reference to the drawings, wherein, I have illustrated the preferred embodiment 35 of my invention as it is reduced to practice, and throughout the several views of which, similar reference numerals designate corresponding parts.

Figure 1 is a front elevation of the face plate of the standard lock illustrating the 40 key-guide in assembled position; Fig. 2 is a section on the line 2—2 of Fig. 1; Fig. 3 is a rear elevation of the guide in disassembled position.

Proceeding now to the description of the drawing the numeral 1 designates the face 45 plate of a standard lock provided with the customary key-hole 2. The guide member consists preferably of a conical shell 3 formed of metal or other suitable material and carries at its apex terminal an integrally formed outwardly extending annular 50 securing flange 4, disposed in lateral relation to the longitudinal axis of the conical shell. The member 4 is provided with a plurality of perforations as at 5 in which 55 are mounted the retaining pins 6. The shell is mounted with the opening at the smaller end in registration with the key-hole 2. In order to permit the insertion of the key-tongue in the key-hole a segment of the shell 60 is cut away as at 7, this segmental cut-away portion being disposed to register with the tongue receiving portion of the key-hole.

What is claimed is:—

A key-guide including a conical shell having an opening formed at the apex thereof, the walls of the shell being provided with a radial outwardly flared segmental opening, the inner end of which is communicant with the said apex opening, an integrally formed 65 outwardly extending securing flange disposed at the apex end of the shell and arranged in lateral relation to the longitudinal axis thereof, means for detachably securing the said flange to the face plate of a lock, 70 said apex opening and segmental opening being of substantially the same size and shape and disposed in registration with the key-hole of the face plate in the assembled 75 position of the guide.

In testimony whereof I affix my signature in presence of two witnesses.

RUFUS K. MULFORD. [L. s.]
